UNITED STATES PATENT OFFICE.

PAUL BUDDE, OF BETHALTO, ILLINOIS.

LEVEL.

1,273,027.

Specification of Letters Patent. Patented July 16, 1918.

Application filed January 26, 1918. Serial No. 213,961.

To all whom it may concern:

Be it known that I, PAUL BUDDE, a citizen of the United States, residing at Bethalto, in the county of Madison and State 5 of Illinois, have invented new and useful Improvements in Levels, of which the following is a specification.

This invention relates to a level, and more particularly to means for illuminating 10 a level which may be otherwise of the standard type.

One of the objects is to provide an illuminating device comprising an electric lamp mounted beneath the level proper and 15 within the body portion or structure within which the level is mounted, this lamp being supplied with current by a cell of any commercial type, and of suitable capacity for the purpose.

20 A further object is to provide certain means of novel construction for mounting the lamp and providing for the electrical connections thereof.

With the foregoing and other objects in 25 view, the invention consists in the novel construction, combination and arrangement of elements hereinafter described and claimed.

In the accompanying drawings:

30 Figure 1 is a view in longitudinal section.

Fig. 2 is a transverse section on line 2—2 of Fig. 1.

Fig. 3 is a perspective view of a lamp 35 supporting member.

The body portion is designated 10 and is provided with a recess 12 receiving a battery 13, the terminals of the battery being designated 14 and 15. One wall of the recess 1: is provided with a metallic plate 16 against which the terminal 14 of the battery is pressed. This plate 16 is in electrical communication with one terminal of the lamp 20 through wire 21 and resilient plate 22. The other terminal 15 of the battery may be placed in communication with the end of wire 24 leading to the lamp base, this connection being shown at 25. Normally the terminal 15 of resilient material is out of engagement with wire 24 but may be placed in engagement therewith when pressure is exerted on element 15.

The resilient plate 22 is provided with a 55 centrally depressed portion 26 for receiving the end of the lamp base and forming elec-

trical connection with the terminal 27 of the lamp. Plate 22 includes deflected portions 28 and outwardly extending members 29 engaging slots 29.

The recess 30 within which the lamp and plate 22 are mounted communicates by means of an opening 32 with a longitudinally extending channel 33 within which the level proper is mounted, this level being 60 designated 34. Beneath plate 22 is a cushioning member 35. The recess or opening 32 is of such cross section that the surface of the lamp will engage the edges of the walls thereof and the resilient member 22 70 will hold the lamp in engaged position, electrical contact being maintained with the terminal 27 as indicated. If desired an aperture 37 may be provided in plate 22 for engaging terminal 27.

75 A plate 40 closes the recess within which the battery is located, and the battery may be merely slipped into position with one terminal 14 in engagement with plate 16. The plate or cover member over the level 80 34 is designated 42.

What is claimed is:

1. In a device of the class described, a body portion, a leveling device mounted therein, said body portion being provided 85 with a recess below the leveling device and with an opening communicating with the recess and located below the leveling device, a lamp within the recess and engaging the walls of the opening, a resilient contact member comprising a plate mounted in the recess and engaging one terminal of the lamp, said plate extending beneath the lamp and exerting upward pressure thereon to retain the lamp in engagement with 90 the edges of the opening, a cushioning member beneath the plate, a battery, means for connecting one terminal of the battery with the plate, and means for connecting the other terminal of the battery with the base of the lamp.

2. In a device of the class described, a body portion, a leveling device mounted therein, said body portion being provided with a channel accommodating the leveling 105 device, an opening in the body portion constituting a recess below the channel, an opening between the opening first named and said channel, a lamp located within the opening or recess first named, means for holding the lamp in position and affording electrical connection therewith, said means

comprising a deflected resilient plate member having a downwardly bent central portion and laterally extending engaging portions, the central portion contacting with one terminal of the lamp, a cushion member mounted beneath the central portion, a battery, a plate member adjacent to one end of the battery and engaging one of the terminals thereof, means for connecting said plate member with the plate first named, 10 and means for connecting the other terminal of the battery at times with the base of the lamp.

In testimony whereof I affix my signature.

PAUL FUDDE.
